UNITED STATES PATENT OFFICE.

JENNIE V. BRENNAN, OF TRENTON, NEW JERSEY.

TIE-SLIDE.

1,269,372.

Specification of Letters Patent. Patented June 11, 1918.

Application filed January 26, 1918. Serial No. 214,005.

To all whom it may concern:

Be it known that I, JENNIE V. BRENNAN, a citizen of the United States, residing at Trenton, in the county of Mercer and State 5 of New Jersey, have invented certain new and useful Improvements in Tie-Slides, of which the following is a specification, reference being had therein to the accompanying drawing.

10 This invention relates to improvements in tie slides adapted to be used in the applying of a necktie to a folded collar, and to facilitate the slipping of the tie through the collar in adjusting the same, to overcome the disadvantages attending the customary position, as will later appear. On these 15 binding of the tie within the fold of the collar, and the attending difficulty of pulling the tie therethrough.

It has been ascertained that the primary binding point of a tie within a folded collar is at the rear collar button used to secure the collar to the neck band of the shirt, the projecting head of the collar button within the fold impinging the tie between the same 20 and the outer fold of the collar. With this in mind, I provide an attachment readily applicable to the tie and designed to temporarily engage the collar and act as an easy slide for the working of the tie through the device, and consequently through the collar, which device will prevent the impinging action of the collar button to which I have alluded; and after the tie has been 25 adjusted and tied into its usual bow or knot at the front of the collar, the device may be readily slipped off of the collar and tied so as not to be carried therewith, it being my intention in this respect to overcome the objection to similar devices where they remain 30 affixed to the collar and tie during the wearing of the latter by the user.

The preferred embodiment of my invention is illustrated in the accompanying drawings forming part hereof and the details of construction and arrangement of parts will be readily understood from an inspection of said drawings in connection with the specific description hereinafter contained.

35 In the drawings,

Figure 1 is a perspective view of the device unattached;

Fig. 2 is a perspective view showing the application of the device to a collar; and 40 Fig. 3 is a transverse sectional view show-

ing the relations of the parts with the tie in place.

Referring more particularly to the drawings, wherein is shown a collar of the ordinary folded type, A represents the outer fold and B the inner fold, provided with the customary rear button-hole C, adapted to receive the collar button D.

The main frame or body of my device is formed of spring wire having parallel vertical portions E, of substantial length and spaced a substantial distance apart so as to occupy positions at opposite sides of the head of the collar button D when placed in the vertical portions to provide a groove, way,

channel to accommodate the head of the collar button. The upper ends of the vertical portions are looped together as at G, the loop being offset forwardly with reference to the collar button to afford a projection for guiding the device in place in its application, but owing to its deflection, preventing any catching of the loop on the collar button when the device is being removed.

The lower ends of the vertical portions are offset outwardly, as at J, and then carried upwardly as at K to furnish relatively shorter vertical portions F' spaced from the plate for the loose reception of the necktie represented at K².

The upper ends of these relatively shorter vertical portions terminate at points where the wire is shaped to constitute return bends L extended downwardly below the remaining portion of the device where they are offset or looped forwardly as at M to merge into still other vertical portions N, bent inwardly toward the intermediate vertical portions as at O, and in a downward direction where they are bridged together at P immediately adjoining or against said intermediate vertical portions to constitute a spring tongue or clamping member. In use the tie is simply slipped into the space permitting the loose engagement of the tie between the intermediate vertical portions and the plate F, and the device and tie are then inserted into the space between the folds of the collar, the outer fold A of the latter being engaged and frictionally gripped between the intermediate vertical portion and the spring tongue, to which I have referred.

When thus applied, the plate F will receive and bear against the head of the collar button and effectually hold the same out of engagement with the necktie so that the necktie may be freely drawn or slipped around when between the folds of the collar.

As soon as the necktie is tied as described, the engagement of the outer part of the device by the fingers will enable its being slipped off or away from the collar and tie, so that the device need not be carried as a part of the collar and tie when in service, the device as previously stated, being primarily intended merely as a temporary assisting medium while the collar and tie are being attached to the wearer.

While I have herein disclosed the preferred embodiment of the invention, it will be apparent to persons skilled in the art to which this invention relates that the same is capable of embodiment in still other forms and devices without departing from the spirit thereof, and as may be embraced within the scope of the hereto appended claims.

Having thus described the invention, what I claim is:

1. A tie slide for folded collars comprising detachable retaining means formed of wire adapted to engage a collar having opposite parallel portions, and a plate mounted on said parallel portions adapted to overlies a collar button to prevent engagement of the collar button with a tie when passed through the fold of a collar.

2. A tie slide composed of wire formed to present three vertical portions spaced apart, each having parallel side members, the inner and intermediate portions affording an unobstructed space for the loose reception of the tie, and the intermediate and

outer portions having a spring closing relation enabling the same to grip a collar fold therebetween, the outer portion being turned inwardly at the upper ends of its side members to constitute an offset to engage the outer face of the collar.

3. A tie slide composed of wire formed to present three vertical portions spaced apart, each having parallel side members the inner and intermediate portions affording an unobstructed space for the loose reception of the tie, and the intermediate and outer portions having a spring closing relation enabling the same to grip a collar fold therebetween, in combination with a plate carried by the inner vertical portion adapted to prevent contact of the head of a collar button with the tie.

4. A tie slide comprising three vertical portions spaced apart, the inner and intermediate portions affording an unobstructed space for the loose reception of the tie, and the intermediate and outer portions having a spring closing relation enabling the same to grip a collar fold therebetween, in combination with means carried by the inner vertical portion adapted to prevent contact of the head of a collar button with the tie, the upper end of the inner vertical portion being deflected outwardly to facilitate introduction of said portion between the folds of the collar, but to prevent engagement thereof with the head of the collar button when the device is being removed.

In testimony whereof I hereunto affix my signature in the presence of two witnesses.

JENNIE V. BRENNAN.
